DESIGN FOR A FLUORESCENT LIGHTING FIXTURE

Max Herr, Chicago, Ill.

Application March 7, 1941, Serial No. 99,407

Term of patent 7 years

To all whom it may concern:

Be it known that I, Max Herr, a citizen of the United States, residing in the city of Chicago, county of Cook, and State of Illinois, have invented a new, original, and ornamental Design for a Fluorescent Lighting Fixture, of which the following is a specification, reference being had to the accompanying drawing, forming part thereof.

Fig. 1 is a top plan view of a fluorescent lighting fixture embodying my new design,

Fig. 2 is a front elevational view of the fixture shown in Fig. 1.

Fig. 3 is an end view of the fixture shown in Fig. 1.

Fig. 4 is a front perspective view of the fixture shown in Fig. 1.

I claim:

The ornamental design for a fluorescent lighting fixture, as shown.

MAX HERR.
